(57) **CLAIM**

(72) Inventor: **Dajun Zhu**, Dongguan (CN)

The ornamental design for a tablet keyboard case with 360-degree biaxial hinge, as shown and described.

(73) Assignee: **Dongguan Bluefinger Electronics Co.,
Limited**, DongGuan (CN)

(**) Term: **15 Years**

(21) Appl. No.: **29/633,472**

DESCRIPTION

(22) Filed: **Jan. 14, 2018**

FIG. 1 is a perspective view of a tablet keyboard case with 360-degree biaxial hinge showing my new design in one of the using positions;

(51) LOC (12) Cl. **14-02**

FIG. 2 is a perspective view thereof, showing another using position;

(52) U.S. Cl.

FIG. 3 is a perspective view thereof, showing the third type of using position;

USPC **D14/440**

FIG. 4 is a front elevational view thereof;

(58) **Field of Classification Search**

FIG. 5 is a rear elevational view thereof;
